Primary Examiner — Karen S Acker*(74) Attorney, Agent, or Firm* — Nancy J. Flint, Attorney At Law, P.A.; Nancy J. Flint, Esq.(57) CLAIM

The ornamental design for a changing table cover, as shown and described.

DESCRIPTION

FIG. 1 is a top perspective view of a changing table cover showing my new design;

FIG. 2 is a front view of the changing table cover;

FIG. 3 is a right side view of the changing table cover; the left side is a mirror image thereof;

FIG. 4 is a top view of the changing table cover;

FIG. 5 is a bottom view of the changing table cover;

FIG. 6 is a perspective view of the changing table cover in a configuration of use;

FIG. 7 is a perspective view of the changing table cover in a second configuration of use; and,

FIG. 8 is a perspective view of the changing table cover in a third configuration of use.

Broken lines in FIGS. 6-8 are for the purpose of illustrating environment that forms no part of the claimed design.

1 Claim, 6 Drawing Sheets
